UNITED STATES PATENT OFFICE

122,278

DESIGN FOR A PRACTICE GOLF GAME BOARD OR SIMILAR ARTICLE

Jack Orman Smith, Fort Worth, Tex.

Application May 15, 1940, Serial No. 92,403

Term of patent 14 years

To all whom it may concern:

Be it known that I, Jack Orman Smith, a citizen of the United States of America, residing at Fort Worth, in the county of Tarrant and State of Texas, have invented a new, original, and ornamental Design for a Practice Golf Game Board or Similar Article, of which the following is a specification, reference being had to the accompanying drawing, forming a part thereof.

In the drawing:

I claim:

The ornamental design for a practice golf game board or similar article, as shown.

JACK ORMAN SMITH.
